UNITED STATES PATENT OFFICE.

HYMAN B. LASTING, OF PORTSMOUTH, VIRGINIA.

GOLF GAME.

Application filed November 2, 1927. Serial No. 230,561.

The present invention relates to a game apparatus particularly designed for the purpose of simulating the art of putting in the well known golf game.

5 One of the prime objects of the invention resides in the provision of an interesting and fascinating game which will enable a golfer to practice the art of putting indoors and attain considerable skill and accuracy.

10 A still further important object of the invention resides in the game apparatus of this nature wherein two or more persons may engage in competitive play.

Another important object of the invention resides in the provision of a game apparatus of this nature which will keep score of the competitors in an automatic manner.

A still further important object of the invention resides in the provision of a game apparatus of this nature which is exceedingly simple in its construction, strong and durable, inexpensive to manufacture, thoroughly efficient and reliable in use, and otherwise well adapted to the purpose for which it is designed.

With the above and numerous other objects in view as will appear as the description proceeds, the invention resides in certain novel features of construction and in the combination and arrangement of parts as will be hereinafter more fully described and claimed.

In the drawings:

Figure 1 is a top plan view of the apparatus embodying the features of my invention,

Figure 2 is a top plan view of the pan thereof,

Figure 3 is a side elevation of the apparatus,

Figure 4 is a longitudinal vertical section taken therethrough substantially on the line 4-4 of Figure 1 looking in the direction of the arrows,

Figure 5 is an enlarged detail vertical section taken substantially on the line 5-5 of Figure 1,

Figure 6 is an enlarged detail plan view showing one of the holes in the platform, and

Figure 7 is a perspective view of one of the markers.

Referring to the drawing in detail it will be seen that the letter A denotes an oblong sheet of material preferably sheet metal with a cloth covering. This sheet A is bent along transverse lines to provide a horizontal putting space 5 said transverse line being indicated at 6 and known as the putt line. The platform sheet then inclines upwardly from the putt line 6 to provide the inclined space 7 which merges into a horizontal relatively large space 8. The side edges of the spaces 7 and 8 preferably diverge from each other from the line 6 so that the sheet A tapers toward the straight portion 5. The end edge of the space 8 is arcuate as is denoted at 9. The spaces 7 and 8 have their side edges provided with depending flanges 10' for resting on the floor or like support. A pan P is disposed under the spaced portion 8 and has an inclined trough 10 terminating adjacent the line 6 and extending alongside of the space 7 as is clearly illustrated in Figure 1. The rear end of this pan is arcuate as at 11 concentric with the edge 9 but on a larger radius so that any golf balls which pass over the arcuate edge 9 will fall into the pan and return to the chute 10. The space 8 of the sheet A is provided with a plurality of openings 12 through which golf balls may pass. One of these openings is shown in detail in its preferred form in Figure 6 and is provided with a radial slot 13 leading therefrom terminating in a cross slot 14.

The golf ball is placed on the space 5 of the sheet A and is hit with a regulation or any sized club to be rolled up the inclined space 7 onto the space 8 the object being to sink the ball in one of the openings 12.

In each opening 12 there is disposed a marker M. Each marker M is preferably formed from a single sheet of metal or like material to comprise a relatively narrow shank portion 15 merging into an L-shaped end portion 16 at one end and offset at its other end as at 17 and merging into a weight or balance element 19 which is formed heavy by bending the material of

which it is made over upon itself. The relatively narrow shank portion 15 is inserted into the cross slot 14 through the radial slot 13. The marker is normally disposed so that the shank portion 15 and the L-shaped end 16 lies flat on the space 8 as is indicated in Figures 1 and 2 and so that the weight element 19 is disposed under the opening as is clearly shown in Figure 4 so that when a ball passes through the opening the weight of the ball on top of the weight element 19 will swing the end 16 upwardly and the shank 15 will slide downwardly through the slit 14 and remain in a vertical position as indicated in dotted lines in Figure 5.

The ends 16 are provided with scoring indicia as is shown in Figure 7. The present showing of the invention there are nine holes 12 and each player is entitled to nine putts and his score will equal the total of the indicia of the markers which are up. This, of course, is only one of the many ways in which the game apparatus may be utilized. It is also to be understood that although I contemplate using standard equipment in the nature of golf balls and clubs that any suitable size may be employed.

It is thought that the construction, utility, and advantages of the invention will now be clearly understood without a more detailed description thereof. The present embodiment of the invention has been disclosed in detail merely by way of example since in actual practice it attains the features of advantage enumerated as desirable in the statement of the invention and the above description. It will be apparent that changes in the details of construction, in the materials, in the sizes, and in the combination and arrangement of parts may be resorted to without departing from the spirit or scope of this invention as herein-after claimed or sacrificing any of its advantages.

Having thus described my invention, what I claim as new is:

1. A game apparatus of the class described comprising a platform having an opening therein, said platform provided with a slot adjacent the opening, a marker having a reduced shank one end of which is offset and merges into a weight element, said reduced shank portion being slidable in the slot so that it may be laid flat on the platform with the weight element under the opening so that a ball passing through the opening will engage the weight element and swing the marker so as to slide downwardly and stand up in the slot at an angle to the platform.

2. A game apparatus of the class described comprising a platform having an opening therein with a slot leading radially

therefrom and merging into a cross slot, a marker comprising a reduced shank portion having one end offset and merging into a weight element and the other end merging into an enlarged portion, the reduced shank portion being slidable in the cross slot and insertible in said cross slot through the radial slot so that the weight element may be disposed under the opening with the offset portion of the reduced shank in the cross slot so that when a ball passes through the opening it will engage the weight element and swing the marker so that the reduced shank will slide down through the cross slot to cause the enlarged end to stand up at an angle in relation to the platform.

3. A game apparatus of the class described comprising a platform having an opening therein with a slot leading radially therefrom and merging into a cross slot, a marker comprising a reduced shank portion having one end offset and merging into a weight element and the other end merging into an enlarged portion, the reduced shank portion being slidable in the cross slot and insertible in said cross slot through the radial slot so that the weight element may be disposed under the opening with the offset portion of the reduced shank in the cross slot so that when a ball passes through the opening it will engage the weight element and swing the marker so that the reduced shank will slide down through the cross slot to cause the enlarged end to stand up at an angle in relation to the platform, said platform having an upper portion in which the opening is enclosed, said upper portion merging into an inclined portion which in turn merges into a lower portion.

4. A game apparatus of the class described comprising a platform having an opening therein with a slot leading radially therefrom and merging into a cross slot, a marker comprising a reduced shank portion having one end offset and merging into a weight element and the other end merging into an enlarged portion, the reduced shank portion being slidable in the cross slot and insertible in said cross slot through the radial slot so that the weight element may be disposed under the opening with the offset portion of the reduced shank in the cross slot so that when a ball passes through the opening it will engage the weight element and swing the marker so that the reduced shank will slide down through the cross slot to cause the enlarged end to stand up at an angle in relation to the platform; said platform having an upper portion in which the opening is enclosed, said upper portion merging into an inclined portion which in turn merges into a lower portion, a pan under the upper portion having a return chute leading therefrom alongside of the inclined portion.

5. A game apparatus comprising a plat-

form having an opening and a slot adjacent to the opening, a marker having a shank slideable in the slot, said shank being offset so that a portion thereof may lie on top of the platform while a portion extends across the opening so that a ball passing through the opening will engage the shank extending

thereacross and swing the marker so that the shank will slide downwardly in the slot and stand up therein at an angle to the platform, 10 and means limiting the downward sliding movement of the shank.

In testimony whereof I affix my signature.

HYMAN B. LASTING.
